[57] CLAIM

The ornamental design for a rotating spice rack, as shown
and described.

DESCRIPTION

FIG. 1 is a front elevational view of the rotating spice rack
showing my new design;

FIG. 2 is a rear elevational view thereof;

FIG. 3 is a left side elevational view thereof;

FIG. 4 is a right side elevational view thereof;

FIG. 5 is a top plan view thereof; and,

FIG. 6 is a bottom plan view thereof.

The broken lines showing the bottle are for illustrative
purposes only and form no part of the claimed design.
